HIS ATTORNEY.

UNITED STATES PATENT OFFICE.

FREDERICK M. VOGEL, OF PITTSFIELD, MASSACHUSETTS, ASSIGNOR TO GENERAL ELECTRIC COMPANY, A CORPORATION OF NEW YORK.

HEATING UNIT.

1,077,658.

Specification of Letters Patent.

Patented Nov. 4, 1913.

Application filed June 12, 1913. Serial No. 773,169.

To all whom it may concern:

Be it known that I, FREDERICK M. VOGEL, a citizen of the United States, residing at Pittsfield, in the county of Berkshire, State of Massachusetts, have invented certain new and useful Improvements in Heating Units, of which the following is a specification.

My invention relates to electric heaters and particularly to a novel heating unit for use in electric ranges, although the novel features of my structure may be used in constructing a heating unit for use with any desired type of heating device.

One of the objects of the invention is to provide an improved means for insulating the resistance element from its carrying frame.

Another object is to so construct the unit that it will not warp out of shape due to repeated heating and cooling and also to so design the same that the resistance element may be easily and quickly replaced in case it should burn out.

Other objects of my invention will appear in the course of the following specification wherein I have fully described one form which my invention may take.

Referring to the drawings, Figure 1 is a plan view of my heating unit the upper portion being shown partly in section; Fig. 2 is an end elevation thereof; Fig. 3 is a side elevation of one of the insulating bushings; Fig. 4 is a section on line 4-4 of Fig. 3.

In the drawing the resistance element 1 is shown as being carried by a rectangular frame made up of two U-shaped side members 2 and 3, and a plurality of cross-strips 4. These cross-strips 4 each comprise two metal strips 5 and 6 suitably fastened together as for instance, by spot welding, and having their ends bent at right angles as shown at 7 to form spacing members. These cross-strips are of such a width that the angular ends fit snugly within the U-shaped side members and only the two end cross strips are fastened to the side members suitable fastening means being shown in the form of screws 8. By this means it will be seen that the parts are free to permit of expansion and contraction and that no warping will result from repeated heating and cooling.

The metal strips 5 and 6 are provided with alined openings 9 having embossed

peripheries as clearly shown in Fig. 4. Clamped by their outer edges between these strips and fitting in the embossed portions of the openings are annular insulating disks 10 to the inner edges of which are fastened metallic rivets 11. These rivets are made of a non-corroding heat resisting metal such for instance, as Monel metal. The resistance element 1 which may be of any desired type and which is here shown as a coiled wire, is made in two sections and is threaded back and forth through the eyelets of the cross strips 4. When the resistance element extends parallel with the cross strips as at the ends, the eyelets carry suitable rings 12 spaced from the cross strips through which the resistance element passes. Two bus rods 13 and 14 one for each section of the heating element and a common bus bar 15 are illustrated, the arrangement of the same being clear from the drawing. By this arrangement a section of the heating element can be quickly replaced without disassembling the frame. I also secure a decided advantage by the arrangement of the insulating bushing in that the heating element is at all points adjacent to metal only whereby any tendency of fluxing which might otherwise take place is avoided.

What I claim as new and desire to secure by Letters Patent of the United States, is:—

1. A heating unit comprising angular side strips, a plurality of cross strips having angularly bent ends loosely supported by said side strips and a resistance element carried by said cross strips.

2. A heating unit comprising U-shaped side strips, a plurality of cross strips having angularly bent ends loosely supported by said side strips, and a resistance element carried by said cross strips.

3. A heating unit comprising U-shaped side strips, a plurality of cross strips each including two members joined together and having their ends angularly bent in opposite directions, said angularly bent ends fitting in said U-shaped side strips, and a resistance element carried by said cross strips.

4. A heating unit comprising U-shaped side strips, a plurality of cross strips each including two members joined together, and having their ends angularly bent in opposite directions, said angularly bent ends fitting in said U-shaped side strips, means for fastening the outermost cross strips to said

side strips, and a resistance element carried by said cross strips.

5. In a heating unit, a metal cross strip having an opening therein, an annular disk of insulating material supported at its outer edge in said opening and a metal eyelet clamping the inner edge of said annular disk.

6. In a heating unit, a metal cross strip having an opening therein, an embossed edge around said opening, an annular disk of insulating material clamped in the embossed edge around said opening, and a metal eyelet clamping the inner edge of said annular disk.

7. In a heating unit, a metal cross strip comprising two members joined together and having aligned openings therethrough, embossed edges around said openings, annular disks of insulating material clamped in said openings between the embossed edges and metal eyelets clamping the inner edges of said annular disks.

8. In a heating unit, a metal cross strip comprising two members joined together and

having aligned openings therethrough, annular disks of insulating material clamped between said members and in said openings and metal eyelets clamping the inner edges of said annular disks.

9. A heating unit comprising U-shaped side members, a plurality of cross strips each including two members joined together and having their ends angularly bent in opposite directions, said angularly bent ends fitting in said U-shaped side members, said cross strips being further provided with openings therethrough, annular disks of insulating material clamped between the members of the respective strips in said openings, metal eyelets clamping the inner edges of said annular disks and a resistance element threaded through said eyelets on said cross strips.

In witness whereof, I have hereunto set my hand this 10th day of June 1913.

FREDERICK M. VOGEL.
